UNITED STATES PATENT OFFICE

YVON BRANCAERT, OF VERRERIES DE FAUQUEZ, RONQUIERES, BELGIUM

TABLE FOR CASTING GLASS SHEETS AND PLATES

Application filed February 14, 1930, Serial No. 428,396, and in Belgium February 21, 1929.

This invention relates to means for improving the cooling of casting tables used in glass works and plate glass works, in order to prolong the existence of such tables which, owing to the high temperatures to which they are subjected when the molten glass is poured thereon, undergo deformations that may cause them to break.

Casting tables are usually cooled by means of a flow of water circulating under the plate and in contact with ribs provided thereon in order to increase its cooling surface. After the plate has been in use for some time, it bulges out under the action of heat, and it may happen that some portions of its under side being raised by this bulging are no longer in contact with the water and become overheated. Moreover steam accumulates under these bulged portions and prevents the water from cooling the table uniformly. Such local overheating is often sufficient to cause the bursting of the plate.

According to the present invention, the first mentioned inconvenience is removed by having the cooling water supply and discharge pipes opening into recesses in the under surface of the plate at points situated above the level of the bulging portions thereof, so that the flow of water tends to settle at a higher level than said portions. On the other hand, the accumulation of steam is avoided by arranging, at the point where the greatest bulging takes place, one or more small pipes which open outside the table, thus permitting the steam to escape from under the plate.

These two devices are shown diagrammatically in the accompanying drawings, in which:

Fig. 1 is a view of the casting table in cross-section through one end.

Fig. 2 shows the table in side view, and

Fig. 3 in longitudinal section.

In these figures, 1 indicates the plate, 2 the ribs of the latter, 3 the chamber for the circulation of cooling water, and 4 the bottom plate of said chamber. The water enters chamber 3 through supply pipes 5 placed at that end of the table which first

undergoes the contact of the molten glass, and is led off through discharge pipes 6 at the other end of the table. These pipes 6 are narrower than the supply pipes 5 in order that the chamber 3 shall always be 55 filled with water.

The two supply pipes 5 are preferably arranged on the sides of the plate 1 and they open into recesses or fountains 7 provided in the under surfaces of the latter. 60 Similar recesses 8 accommodate the upper ends of the discharge pipes 6 at the other end of the table, so that the water is supplied and discharged at a level above the under surface of the plate and thus washes 65 all the parts of the latter, even those that are bulged out.

In the central portion of plate 1, where the bulging is greatest and where the steam evolved from the cooling water tends to accumulate, a small pipe 9 which may open into a recess 10 (Fig. 1) or simply underneath the plate (Fig. 3), and extends upwards through the chamber 3 and plate 4, evacuates the steam outside the table as soon 70 as it is formed. This small pipe 9 is given a very small sectional area so that only small quantities of water are allowed to run out through it when there is no steam to be ejected. 75

The invention may be applied to movable casting tables as well as to ordinary stationary tables.

I claim:

1. A table for casting glass sheets and plates comprising a glass receiving plate 85 said plate extending over the entire surface of said table, a chamber under said plate, a closure for said chamber, two recesses in the underside of said plate, an inlet and an outlet pipe each opening into one of said recesses. 90

2. A table for casting glass sheets and plates comprising a metal plate extending over the entire surface of said table for receiving the glass, said plate having a ribbed underside, a chamber under said plate, means for closing said chamber, two water pipes opening each into said chamber at a 95 level above the underside of said plate, and 100

means for evacuating steam from the top of said chamber.

3. A table for casting glass sheets and plates comprising a metal plate for receiving the glass, said plate having ribs on its underside and grooves between said ribs, a chamber under said plate, a bottom plate closing said chamber, two recesses located each in one of said grooves at opposite ends 10 of said chamber, two water pipes opening each into one of said recesses at a level above the bottom of said grooves and a steam outlet tube of small cross-section leading from the top of the central portion of said 15 chamber.

4. A table for casting glass sheets and plates comprising a metal plate for receiving the glass, a chamber under said plate, a closure for said chamber, two recesses in the 20 underside of said plate, two water pipes each opening into one of said recesses, and a steam evacuating pipe of small cross section opening into the top portion of said chamber.

25 5. A table for casting glass sheets and plates comprising a metal plate for receiving the glass, a chamber under said plate, a closure for said chamber, three recesses in the underside of said plate, and three pipes 30 each opening into one of said recesses, one of said pipes being of very small cross section.
